BOTTLE VENDING MACHINE

Max Hermann Voigtritter, Chicago, Ill., assignor
to Mills Novelty Company, Chicago, Ill., a corporation of Illinois

Application July 3, 1939, Serial No. 282,659

17 Claims. (Cl. 312—87)

This invention relates to bottle vending machines of the type in which a plurality of bottles are suspended in a refrigerated casing by means of an endless carrier which conveys the bottles successively to a position from which they are elevated into a delivery opening in the top of the casing, where they may be grasped by the hand of the customer. A machine of this type is disclosed in my co-pending application, filed October 21, 1937, Serial No. 170,230, and the object of the present invention in general is to improve in certain respects upon the construction shown in that application.

One object of the invention is to provide an improved arrangement for detecting when the supply of bottles in the machine has become exhausted or has reached a low point, or when an interruption occurs in the succession of bottles being fed to the delivery opening. This mechanism will prevent further operation of the machine and cause the display of an "empty" indicator upon the occurrence of a single unfilled space in the conveyor at a predetermined point near the delivery opening, whereas in prior devices such a single space might be allowed to pass without effect upon the subsequent operation of the machine.

Another object of the present invention is to provide an arrangement in which such mechanism will be temporarily actuated during each operation of the machine, so as to return to the customer any coin inserted while the machine is in operation, without operating said indicator.

A further object of the invention is to improve upon the conveying and elevating mechanism so as to render the transfer of bottles from the conveyor to the delivery opening more certain, to reduce bottle wear and injury, and to eliminate the possibility of bottles becoming disengaged from the conveyor before they reach the delivery opening.

Other objects and advantages of the invention will become apparent from the following detailed description, which, taken in connection with the accompanying drawings, discloses a preferred embodiment thereof.

Referring to the drawings:

Fig. 1 is a front elevation of a bottle vending machine embodying my invention;

Fig. 1a is a plan view on the plane 1a—1a in Fig. 1, the cover and the operating head being removed to illustrate the interior construction of the machine;

Fig. 2 is a longitudinal, vertical section of the same, taken on the line 2—2 of Fig. 1a;

Fig. 3 is a partial transverse section taken substantially on the line 3—3 of Fig. 2, illustrating the elevating mechanism in side elevation;

Fig. 4 is a similar view of said mechanism, taken substantially on the line 4—4 of Fig. 2;

Fig. 5 is a horizontal, sectional view taken substantially on the line 5—5 of Fig. 2;

Fig. 6 is a detail sectional view illustrating the mounting of the conveyor rails;

Fig. 7 is a detail view of the latch for latching the elevating mechanism in inoperative position;

Fig. 8 is a vertical sectional view through the casing of the operating head showing the mechanism in front elevation;

Fig. 9 is a right angle view of said mechanism, taken on the line 9—9 of Fig. 8;

Fig. 10 is a horizontal sectional view of certain parts of said mechanism, taken on the line 10—10 of Fig. 8;

Fig. 11 is a detail view, taken on the line 11—11 of Fig. 10;

Fig. 12 is an elevational view of the gearing beneath the operating head, being taken on the line 12—12 of Fig. 1a;

Fig. 13 is a sectional view, taken on the line 13—13 of Fig. 1a; and

Fig. 14 is a perspective view of the trigger mechanism.

Upon said drawings, the reference numeral 10 indicates a casing which may hold a body of cold water in which the bottles to be vended are partially immersed. The water may be refrigerated by means of ice, or by means of a refrigerating coil 11 (Fig. 2), through which a suitable refrigerant, as, for example, an evaporative refrigerant compressed by a compressor employed in conjunction with the machine, may be circulated.

In the upper region of the casing 10 is secured a horizontal frame 12 on which the operating mechanism within the casing is supported.

The bottles, which are indicated in Fig. 2 and elsewhere by the letter B, are supported in holders designated generally by the reference character H, such holders being suspended from rollers 13 which travel upon rails 14 suspended from the frame 12.

The rollers 13 are secured to an endless conveyor chain 15 by means of yoke-shaped brackets 16 in which the rollers 13 are journaled and to which the holders H are attached by means to be later described.

Referring to Fig. 1a, the chain 15 travels around sprockets 17, 18, 19, 20, 21, 22, and 23 in the order named, the sprockets 17, 18, 19, 20, and

21 being staggered with relation to each other so as to provide a series of substantially parallel stretches 24, 25, 26, and 27 of the chain 15, occupying the major portion of the space within the casing 10. The sprockets 22 and 23 guide the chain from the sprocket 21 around three sides of the interior of the machine to the pulley 17, forming a side stretch 28, an end stretch 29, and another side stretch 30 in the order named.

The conveyor moves in the direction indicated by the arrow 31, lower right of Fig. 1a. As the holders H turn the corner beneath the sprocket 23 and commence the stretch beneath the reach 30, they approach the elevating mechanism which is indicated generally by the reference character E in Fig. 2.

Said elevating mechanism E comprises a pair of spaced, channel-shaped guideways 32 (Figs. 2, 3 and 4), the ends of which are splayed, as indicated by the numeral 33, and secured to cross plates 34. Said guideways 32 are attached at their upper ends to the frame 12 by means of bolts 35 extended through the frame and through the splayed ends 33 of the guideways and the cross plates 34.

Mounted between the guideways 32 for vertical movement is an elevator carriage 36. Rollers 37, mounted on studs projecting from the corners of the carriage 36 are received between side flanges 39 of the guideways 32 and allow the carriage 36 to travel freely up and down between the guideways. (See Fig. 5.)

In the rear side of the carriage 36 is a vertically extending recess 40, at the upper end of which is a lug 41. A lifting chain 42 is attached to the carriage by an eye-bolt 43 extending through the lug 41 into the recess 40 and secured by nuts 44 threaded thereon and engaging the upper and lower sides of the lug 41.

The chain 42 extends upwardly through an opening 45 in the plate 12, said opening being shown in Fig. 1a.

The elevator E is located on the outer side of the reach 30 of the conveyor. On the other side of the reach 30, opposite the elevator E, is the mechanism, indicated generally at D in Figs. 3 and 4, which receives the bottle from the elevator, guides it upwardly through a delivery mouth 46 in the frame 12, shown in Figs. 1a and 3, and supports it in that position until it is removed by the purchaser. In the elevating operation, the bottle must be removed from the holder H and moved laterally from a position centered beneath the conveyor chain 15 to a position aligned with the axis of the opening 46. This is accomplished in the embodiment of the invention shown by swinging the entire bottle holder laterally until the lower region thereof contacts an apron 47 of the delivery guide mechanism D, shown in Figs. 3 and 4.

Such lateral movement is effected by means of a bottle engaging finger 48 formed integrally with the carriage 36 and projecting laterally from the lower central region thereof. The upper surface of the finger 48 is inclined downwardly, as indicated at 49, toward the end of the finger. The bottle is first engaged at the upper extremity of the inclined surface 49, as shown in Fig. 3, and moves downwardly and outwardly on said inclined surface as the finger 48 moves upwardly.

As the holder H contacts the apron 47 of the delivery guide mechanism, the bottle and holder will have swung from the initial position shown in Fig. 3 to the position shown in full lines in Fig. 4.

The bottle holder H is preferably constructed so that the holder, rather than the bottle, makes the first contact with the apron 47. The object of this construction is to protect the bottle from chipping and wearing as a result of the impact against the apron. To this end, the lower region of the holder H has a portion 51 extending around the bottle on the side toward the apron. The opposite side of the holder is open from top to bottom, and the bottom is open with the exception of a flange 52 extending inwardly to form a seat for the bottle, so that the elevator finger 48 may move upwardly from a position below the holder, engage the bottom of the bottle, and then move upwardly between side members 53 of the holder as it raises the bottle out of the holder and into the delivery mechanism. The portion 51 of the holder, in addition to serving as a guard member, also serves as a bridging connection between the side members 53. The upper ends of said side members 53 are secured at 54 to side members 55 of a fork-shaped hanger 56, having a web portion 57 connecting the arms 55 and secured at 58 to the roller bracket 16.

In contrast to prior arrangements, in which the rail is above the chain and the chain is disposed between the roller bracket and the bottle holder, so that the weight of the bottle holder and bottle is at all times imposed upon the chain, the chain in the present construction is located above the roller, so that when the roller is traveling on the rail, the chain is supported on the roller bracket and under no strain. Only when the holders are traveling beneath a sprocket is the weight thereof imposed upon the chain.

Returning the elevating mechanism as shown in Figs. 3 and 4, it may be noted that the finger 48 at its outer end has its under side inclined upwardly as indicated at 62. After the elevator has completely elevated the bottle, the carriage is released and allowed to drop back to starting position. Should the bottle holder happen to have swung to a position in which the end of the descending finger 48 would strike the flange 52 of the bottle holder, the inclined face 62 would push the bottle holder away and avoid jamming.

The side of the carriage 36 which faces the bottle is provided with a recess 63 (Fig. 4) extending from the finger 48 to the top of the carriage. The bottle, as it approaches the elevator, moves into the recess by riding against an inwardly inclined guide bar 200 (Figs. 2 and 5) which is attached to the carriage 36 and moves therewith. The recess 63 serves to position the bottle in centered relation to the finger 48. The finger 48 is relatively narrow and its sides are tapered toward its outer end, so as to avoid jamming of the finger against the flange 52 on the holder H.

The delivery guide mechanism D in addition to the apron 47 includes a sleeve 64 above, and as shown integral with, said apron, the upper end of said sleeve being provided with a flange 65 secured at 66 to the underside of a flange 129 defining the opening 46 in the frame 12. The lower region of the apron 47 is inclined downwardly and inwardly toward the center of the sleeve as indicated at 68 and terminates in an outwardly inclined lip 69 which the portion 51 of the holder H is adapted to engage when said holder is swung outwardly, as shown in Fig. 4.

A trap door 73 is provided in the sleeve 64, being hinged to ears 70 on said sleeve by means of a hinge pin 71 extending through said ears 70 and through ears 72 on the door. Said door nor-

mally rests in a horizontal position as shown in Fig. 4, being urged toward that position by a spring 74 coiled around the hinge pin 71, said spring having one end 75 engaging the top of the trap door 73 and the other end 76 hooked into one of the ears 70.

The side central portions of said trap door 73 rest upon heads 77 of latch arms 78, said arms being disposed outside of the sleeve 64 on opposite sides thereof, and the heads 77 projecting laterally through openings 79 in said sleeve. The ends of the arms 78 opposite the heads 77 are pivotally attached to lugs on the sleeve 64, by means of pintles 82 and a spring 83 is stretched between projections 84 on the respective arms 78 and urges said arms toward each other.

As the bottle B moves upwardly through the sleeve 64, it will engage and lift the trap door 73 and will then engage the inner faces of the heads 77, which faces are inclined downwardly and outwardly, and will thereby spread the latch arms 78 until it has passed them.

The sleeve 64 is cut away at 85 to provide clearance for the trap door 73 when the latter is thus lifted. A stop 86 formed integrally on and projecting downwardly from the flange 65 is engaged by the upper end of the trap door 73 when the latter is in raised position and limits its movement.

Said trap door 73 serves, when in closed position, to prevent unauthorized access to a bottle beneath the delivery opening, and when in raised position, it exerts yielding pressure against the bottle to oppose the tendency of the latter to tilt toward the right, viewing Figs. 3 and 4, under the upward pressure of the lifting finger 48, thus aiding in guiding the bottle in a properly centered position into the delivery opening.

Referring now to Figs. 1a and 2, the elevator operating chain 42, after passing through the opening 45, passes over a pulley 87 journaled between two upwardly projecting ears 88 of a bracket 89, which is secured against the upper face of the frame 12 by means of screws 35. From the pulley 87 said chain extends to the left, viewing Fig. 2, to form part of a movement multiplying mechanism including a pulley 90 journaled in a bracket 91 secured to the end of an elevator operating bar 92; a pulley 93 journaled in the bracket 89; and a pulley 94 journaled in the bracket 91. The chain 42 extends around these pulleys in the order named, and its end is fastened in an ear 95, bent laterally from one of the walls 88 of the bracket 89. The bracket 91 is U-shaped, as viewed from above, and is attached to a downwardly-turned portion 96 on the end of the arm 92, shown in dotted lines in Fig. 2.

The operating mechanism is mounted on a base 97 (Figs. 1 and 2) which is secured to the frame 12 by means of screws 98. Journaled on a post 99 (Fig. 12) mounted in the base 97 is a drive pinion 100, adapted to be rotated by a coin-controlled mechanism to be hereinafter described. Journaled upon a post 101 and supported upon a boss 102 projecting upwardly from the base 97, in which boss the post 101 is mounted, is a gear 103 which meshes with the pinion 100 and is driven thereby.

The conveyor is driven by a Geneva drive mechanism including a driver 104 formed integrally with the gear 103 and a driven member 105 having six recesses 106 to receive at intervals pins 107 on the driver, there being three such pins shown in the drawings.

The driven member 105 is mounted on a spindle 75

108 journaled in a bearing 109 in the base 97 and projecting through the frame 12, below which it carries the drive sprocket 17 of the conveyor.

Projecting from the lower side of the pinion 100 is an arm 110 on the end of which is journaled a roller 111 (see Fig. 1a). The arm 110 operates the elevating mechanism, as will presently appear.

Referring again to the elevating mechanism, 10 the bar 92 is slidably mounted on top of the base 97 between rollers 112 journaled on studs 113 projecting upwardly from the base 97. Slidably mounted on top of the bar 92 is a second bar 114 which is likewise guided between the rollers 112. The bar 114 has a laterally projecting finger 115 which is adapted to be engaged by the roller 111 as the pinion 100 and arm 110 rotate through one operating revolution in clockwise direction (viewing Fig. 1a). Engaging the finger on its right side, as viewed in said Fig. 1a, the roller 111 will move the bar 114 to the left. The bar 114 will carry with it in this movement the lower bar 92 by reason of the connection of the left end of the bar 114 with a hook 117 formed on the end of the bar 92 and extending around and above the end of the bar 114. This movement of the bar 92 will cause the pulleys 90 and 94 to extend the reaches of the chain 42, drawing up the lower end of the latter and raising the elevator carriage 36 to a position near the top of the guideways 32.

The hook 117 is connected by a coil spring 118 to the upper bar 114, one end of the coil spring being attached to the hook and the other end to a pin 119 projecting upwardly from the bar 114. The spring 118 normally maintains the bar 114 in its position shown with its end in contact with the hook 117, but allows the bar 114 to be moved sufficiently to the right, viewing Fig. 1a, to remove the finger 115 from the path of the roller 111. This is for the purpose of rendering the elevating mechanism inoperative while the conveying mechanism remains operable, for loading purposes, the operator being able to continuously operate the conveying mechanism with his left hand while with his right hand inserting bottles into successive holders passing a given position in the machine. The loading is preferably executed through the triangular-shaped loading space S in the frame 12, where access may be had to either the reach 29 or the portions of the conveyor passing around sprockets 20 and 18.

The bar 114 may be moved to inoperative position by means of a handle 120 formed on the end of a portion 121 of the bar 114, the portion 121 being offset to clear the pulley yoke 91. The bar 114 may be latched in inoperative position by a latch lever 122, shown in Figs. 2 and 7. The lever 122 is pivoted on a shaft 123 on which the pulley 93 is also mounted. Its end toward the bar 114 is provided with a latching hook 124 positioned to engage beneath the handle 120 as the latter is pulled to the right, to be depressed thereby and to latch behind the same under the pull of a spring 125, one end of which is attached to a finger 126 projecting upwardly from the lever 122, and the other end of which is attached to a pin 127 mounted in the wall 88 of the bracket 89 (see Fig. 1a). A tail 128 forming the other end of the lever 122 engages the frame adjacent the delivery mouth 46 to limit the upward movement of the latch hook 124 to a position which will permit the handle 120 to ride over it.

The latch lever 122 has an upwardly projecting trigger 130, the upper end of which is adapted to be engaged by a hinged cover 131 forming a part

of the top of the casing as said cover is moved to closed position after the refilling operation is completed. This causes the latch to be released, allowing the elevator operating arm 114 to return to operative position.

In normal operation the conveyor and elevating mechanism are operated from the coin-controlled operating head shown in detail in Figs. 8-11 of the drawings.

As shown in Figs. 8 and 1a, an operating shaft 99a depending from the operating head, is adapted to rotate the pinion 100 to which is loosely coupled at its lower end by means of a transverse coupling pin 99b mounted in its lower end and engageable in notches 99c in a collar 99d on the top of the pinion. 15

The operating head is mounted in a casing 175 which is flanged at the bottom and secured by screws 176 to a portion 177 of the top wall of the cabinet 10 over an opening 178 in said wall. Said head includes a bracket 132 attachable at its lower end to supporting bars 133 carried by the base 97. 20

In the upper part of the bracket 132 is journaled a shaft 134 carrying a bevel gear 135 meshing with a bevel gear 136 secured on the upper end of the operating shaft 99a. On the other end of the shaft 134 is a crank handle 137. 25

The shaft 99a is normally locked against rotation by a coin-controlled mechanism including a coin-receiving slot 138, a selector mechanism, indicated in rough outline form at 139, and a locking lever 140 carrying at its end a coin-receiving pocket 141 in registry with the lower end of a good-coin delivery chute 142 of the selector unit. A feeler pin 140a carried by an arm 140b, which is adapted to be actuated by the initial rotation of the shaft 99a, is movable into the pocket 141 and if a coin is present therein it will serve as a medium to transmit the motion of the arm 140b to the lever 140 to move the same out of its normal position in which it prevents complete rotation of the shaft 99a. Details of this coin mechanism are shown and described in my application, Serial No. 170,230, above referred to, and reference is made to that application for a fuller explanation thereof. 30

The mechanism for causing rejection of coins when the machine is in operation and when an interruption occurs in the succession of bottles being fed to the elevator includes a lever 143 (see particularly Figs. 10 and 11) pivoted on a post 144 mounted on an ear 145 formed on the back plate 146 of the coin selector unit 139. The upper end of the lever 143 has a finger 147 projecting into the path of movement of the coins into the good-coin chute 142 as they are directed thereto after passing between magnets 148 forming part of the selector unit. The central part of the lever 143 whereby said lever is mounted on the post 144 is in the form of a yoke, identified by the numeral 149. A weighted arm 150 projecting from said yoke 149 serves to normally maintain the lever 143 in position with the finger 147 out of the path of the coins. 35

Engaging the under side of the yoke 149 is a finger 151 on a lever 152 which has a yoke portion 153 pivoted on a post 154 mounted in the ear 145. The other end of said lever 152 is attached to a rod 155 projecting downwardly through an opening 156 in the base of the bracket 132. Formed integrally with the yoke portion 153 of said lever 152 and projecting in the same direction as the finger 151 is an arm 157. The outer end of the arm 157 has a laterally projecting ear 158 through which extends a vertical rod 159. The 40

upper end of said rod 159 is attached to one end of a lever 160 pivoted at 161 on an ear 162 formed on the back plate 146, the other end of the lever 160 being formed with a visible indicator 163 bearing the word "empty" as shown at 164 in Fig. 8. 45

A lost-motion connection is provided between the rod 159 and the lever arm 157, comprising a pair of collars 165, 166 secured to the rod 159 in spaced relation, and a spring 167 disposed between the lower collar 166 and the ear 158 on the arm 157, said ear being slideable on said rod beneath the collar 165. The purpose of this lost-motion connection is to allow the lever 152 to operate the blocking lever 143 during the initial stage of its movement and before operating the indicator 163. 50

The mechanism for operating the above-described lever 152 is designed to cause the latter to have a limited movement upon each vending operation of the machine, so as to cause any coins inserted during a cycle of operation to be rejected, such limited movement not affecting the visible indicator, and to have a longer stroke when an interruption occurs in the bottle supply, so as to operate both the blocking lever and the visible indicator. This mechanism will now be described, attention being called particularly to Figs. 2, 3, 4 and 14. 55

From Figs. 2 and 14 it will be observed that the lower end of the rod 155 is normally supported by a lateral projection 170 on the end of one arm of a bell crank lever 171 pivoted at 172 on an upwardly projecting post 173 on the base 97. As long as the rod 155 is thus supported, the lever 152 is maintained in a position in which the visible indicator 163 is in the raised position shown in full lines in Fig. 9, and the lever 143 is in the non-obstructing position shown in Fig. 11. When the support of the rod 155 is withdrawn, the indicator 163 is allowed to drop to the dotted-line position shown in Fig. 9 wherein it is visible through a window 174 in the casing 175 of the operating head, the weight of the indicator 163 and rod 155 at the same time causing the lever 143 to move into position to block entrance of coins into the chute 142. 60

The bell crank lever 171 is normally maintained in position shown in Fig. 2 by the engagement of a pin 182 (Figs. 2 and 14) mounted in the yoke 91, against the intermediate region of a vertically disposed lever 183, the upper end of which is linked by a rod 184 to an upwardly projecting arm 185 of the bell crank lever 171. The position shown in Fig. 2 is maintained as long as the machine is at rest. When elevator slide bar 92 and yoke 91 commence to move to the left, as viewed in Figs. 2 and 14, thus causing the pin 182 to move away from the lever 183, the downward push of the rod 155 on the lever 171 causes the rod 184 to move the lever 183 to the left to an intermediate position, limited by the engagement of the lever against a pin 186 extending through an elongated slot 187 in said lever 183 and mounted in an ear 188 on a bracket 188a secured to the frame 12. During this movement, the lever 183 fulcrums around its lower end, where it is provided with a laterally bent lug 189 engaging against the vertical edge of a step 190 formed in one end of a trigger 191 which is pivoted at 192 on an ear 193 on the bracket 188a. 65

This is the position in which the coin-blocking lever 143 is rendered operative while the visible indicator 163 remains inoperative, and it will be obvious from the foregoing that the coin 70

mechanism will be conditioned to reject coins during a major portion of each operating cycle of the machine, beginning shortly after the elevator commences to travel upwardly, and terminating when the elevator has almost reached the bottom of its movement on the return journey.

In order to confine the movement of the lever 183 within predetermined limits, the trigger 191 is provided with a second shoulder, 191a, and with a finger 191b, both projecting above the step 190 and being located on opposite sides thereof. A narrow neck portion 191c of the trigger 191 between the finger 191b and the shoulder 190 is engaged by the lug 189 in the normal position of the parts shown in Fig. 2, to support the trigger in the position shown. A lug 189a on the lower end of the lever 183 limits the downward movement of the left end of the trigger.

The other end of the trigger 191 projects into the path of movement of a pawl 194 (see Figs. 2-5) mounted in the elevator carriage 36 on a shaft 195 which is journaled in bearings 196 on said carriage.

The shaft 195 projects past the guideway 32 on the side toward the approaching bottle holder, and is provided with a laterally-turned arm 197 which normally projects beneath the position of the bottle next following the one that is in position to be elevated, said arm having at its end a fork 198 in which is journaled a roller 199 which contacts the bottle referred to as the carriage 36 moves upwardly, and rides along the side of the bottle. In doing so, the arm 197 is forced to assume a downwardly inclined position, causing the shaft 195 to rotate so as to move the pawl 194 into the recess 40 in the carriage 36, in which position the pawl 194 will clear by the trigger 191 when the elevator is raised.

The pawl will be held in this position by a friction yoke 216, secured to the pawl and extending into the recess 40 and frictionally engaging the sides thereof. When the elevator returns to its starting position the roller 199 will engage the cross plate 34 of the elevator guideway and will be thereby returned to its normal position shown in Fig. 3.

In order to prevent the bottle from swinging away from the arm 197 under the pressure of the latter, I provide a rest 202 (Fig. 5) secured to the lower end of the apron 68 and having a curved end 203 adapted to engage the portion 51 of the bottle holder positioned opposite the arm 197.

When no bottle is present in the holder opposite the arm 197, the pawl 194 will be held in its outwardly projecting position by the frictional engagement of yoke 216 in the recess 40 and, as the elevator nears the top of its travel, will engage the trigger 191 to move the left end of the latter downwardly, releasing the lug 189 of the lever 183 from the step 190 and allowing the lever 183 to pivot around the pin 186 to a third position (shown in Fig. 14) in which the portion 170 of the lever 171 and the rod 155 are further lowered and both the visible indicator 163 and the blocking lever 143 are rendered operative.

The lever 183 will remain in this position, engaging above the step 190 and holding the lever 191 in the position to which it has been moved by the pawl 194, until it is reset by the operator.

It will now be evident that when a single bottle is missing in the succession, the machine will be locked against operation and the visible indicator will be displayed when the empty holder reaches the position just ahead of the elevator.

Each of the rails 14 is laterally offset as at

205 (Figs. 1a-4) to clear the bottle holder, and has a downwardly projecting body portion 206 by means of which it is supported from the frame 12. The rails 14 are terminated short of the axes 5 of the respective sprockets, but the body portions 206 of the respective rails extend beyond the ends of the rails 14 for attachment to supporting brackets. Where the reaches of the chain 15 curve away from the rail ends, the body portions 206 of those ends extend beyond the sprockets and are provided with upwardly extending bracket portions 207, the upper ends of which are secured to the lower side of the frame 12. Where the chain curves around the ends of the rails, as in connection with the sprockets 18 and 20, the ends of the body portions 206 are secured to downwardly depending side arms of yoke-shaped brackets 208, the web portions of which are mounted on the lower ends of respective sprocket shafts 209 which are supported in the frame 12 and on which the sprockets are rotatably mounted.

In order to adjust the tension of the conveyor chain 15, an adjustment is provided for the sprocket 18, including an L-shaped bracket 210 (Fig. 1a) in which the upper end of the shaft 209 is mounted; a threaded rod 211 mounted in the upwardly projecting arm of the bracket 210; and nuts 212 threaded onto the rod 211 and engaging the opposite sides of an ear 213 projecting upwardly from the frame 12. Movement of the shaft 209 relative to the frame 12 is accommodated by an elongated opening 214 in the frame, through which the shaft projects.

The movement of the yoke 208, which is caused by adjusting the sprocket 18, is allowed by a sliding connection between the rail beneath the reach 25 and the yoke 208, on the one hand, and a sliding connection between the opposite end of the rail beneath the reach 24 of the chain, and the frame 12. The first-mentioned sliding connection comprises a screw 214', extended through an elongated opening 215 in the body portion of the rail beneath the reach 25, and threaded into the yoke 208. The second-mentioned sliding connection comprises a bolt 216, extended through a slot 217 in the bracket portion 207, and secured in the frame 12. Thus the ends of the rails which support the regions of the chain approaching the respective sprockets are maintained in fixed relation to the sprockets so as to avoid any possibility of the chain sagging sufficiently to run off a sprocket.

The cover sections 131 and 177 are hinged together at 179 and are provided with marginal flanges 180 to rest upon the upper edges of the walls of the casing 10. The cover sections and the casing 10 are of double-wall construction, filled with insulating material 181. The outlet opening in the cover section 131 is indicated by the numeral 46a. A coin-return tray is shown at 142a.

In the operation of the machine, a coin is inserted in the receiving opening 138, and the crank 137 is rotated through one revolution. The bevel gears 135 and 136 transfer this rotative movement to the shaft 99a and then to the pinion 100, which drives the gear 103. The Geneva driver 104, formed integrally with the gear 103 will, after the crank has been turned a short distance, engage the driven member 105 and, during about 90 degrees of rotation of the driver 104, will rotate the shaft 108 sixty degrees. This will cause the conveyor chain to be advanced a distance corresponding to the distance between two bottle holders, and a full holder will be posi-

tioned opposite the elevator carriage 36. After a very short interval, the roller 111 of the arm 110 will engage the finger 115 of the elevator slide bar 114, drawing the bar 114 and with it the bar 92 to the left, as viewed in Fig. 1a.

This will cause the elevator carriage 36 to move upwardly between the guideways 32, whereupon the finger 48 will engage the bottle, swing the bottle and its holder laterally against the apron 68, then tilt the upper end of the bottle into the apron 68, and then raise the bottle into the sleeve 64 and through the mouth 46.

After the elevator has traveled a short distance, the pin 182 will release the lever 183 to a position where the coin-blocking lever 143 is temporarily rendered operative to block any coins subsequently inserted in the opening 138, and cause them to be returned to the operator through the coin-return chute 142a. The coin mechanism will remain thus locked until the cycle of operation of the machine is almost completed, whereupon the pin 182 will again engage the lever 183 and move the blocking lever 143 to inoperative position.

If a bottle is present in the next holder, the pawl 194 will be moved to inoperative position and will pass by the trigger 191 without affecting the "empty" indicator. If a bottle is absent from the said holder, the pawl 194 will, when the carriage 36 nears the top of its journey, engage the trigger 191 to release the lever 183 and allow the "empty" indicator to drop to indicating position. The releasing of the lever 183 will also cause the coin chute to remain blocked until the operator refills the machine, as a result of the lower end of the lever 183 having been shifted to the right so that even though the pin 182 returns to normal position, shown in Fig. 2, as the elevator returns to its position of rest, the upper end of the lever 183 will not be held far enough to the right to retract the lever 143. After filling the machine, the operator may reset the trigger by moving the upper end of the lever 183 to the right until the lug 189 clears the step 190, allowing the trigger to move under the weight of its longer right portion, back to the position shown in Fig. 2.

The foregoing detailed description has been given for clearness of understanding only, and no unnecessary limitations should be understood therefrom, but the appended claims should be construed as broadly as permissible in view of the prior art.

I claim as my invention:

1. In a bottle dispensing machine, a casing having a bottle delivery opening, means for feeding bottles successively to a position in the vicinity of said opening, means for projecting a bottle thus positioned into said opening, and a device for rendering the machine inoperative upon the occurrence of an interruption in the succession of bottles approaching the opening, said device including a feeler carried by said bottle-projecting means and adapted to travel longitudinally of and in contact with the side of a bottle subsequent in the line of succession to the one being projected, and means controlled by said feeler and adapted to render said device ineffective as long as there is a bottle in position to be contacted by said feeler and to render the same effective when no bottle is present in said position to prevent further operation of the machine until said device is reset by the operator.

2. In a bottle dispensing machine, a casing having a bottle delivery opening, means for feed-

ing bottles successively to a position in the vicinity of said opening, means for projecting a bottle thus positioned into said opening, and a device for rendering the machine inoperative upon the occurrence of an interruption in the succession of bottles approaching said opening, said device including a feeler carried by said bottle-projecting means and adapted to contact the side of a bottle subsequent in the line of succession to the one being projected, to render said device ineffective as long as there is a bottle in position to be contacted by said feeler and to render the same effective when no bottle is present in said position to prevent further operation of the machine until said device is reset by the operator.

3. In a bottle dispensing machine, a casing having a bottle delivery opening, means for feeding bottles successively to a position in the vicinity of said opening, means for projecting a bottle thus positioned into said opening, a device for rendering the machine inoperative upon the occurrence of an interruption in the succession of bottles approaching said opening, and means for operating said device, said operating means including a feeler carried by said bottle-projecting means and adapted to travel longitudinally of and in contact with the side of a bottle subsequent in the line of succession to the one being projected, a trigger-actuating pawl carried by said bottle-projecting means and operatively connected to said feeler so that its position is determined by the position of the feeler, a trigger disposed in the path of said pawl as positioned when said feeler is not in engagement with a bottle and being clear of the path of said pawl as positioned when said follower is in engagement with a bottle, and means controlled by said trigger when actuated by said pawl for causing actuation of said operating means.

4. In a bottle vending machine, a casing having a bottle delivery opening, means for successively projecting a plurality of bottles into said opening, a device for rendering the machine inoperative at certain times, an indicator for indicating interruption of the bottle supply, and means for operating said device and said indicator, said operating means being constructed and arranged to maintain both the indicator and said device in inoperative position when the bottle-projecting means is in its normal position of rest, to render said device but not said indicator temporarily operative during each projection of a bottle, and to render both said device and said indicator operative upon interruption of the supply of bottles to said projecting means.

5. In a bottle vending machine, a casing having a bottle delivery opening, means for successively projecting a plurality of bottles into said opening, a device for rendering the machine inoperative at certain times, an indicator for indicating interruption of the bottle supply, and means for operating said device and said indicator, said operating means being constructed and arranged to maintain both the indicator and said device in inoperative position when the bottle-projecting means is in its normal position of rest, to render said device but not said indicator temporarily operative during each projection of a bottle, and to render both said device and said indicator operative upon interruption of the supply of bottles to said projecting means, said operating means including means movable a limited distance upon each operation of the machine to render said operation-preventing device temporarily effective during the cycle of operation and movable a fur-

ther distance to operate said indicator when such interruption of the bottle supply occurs.

6. In a bottle vending machine, a casing having a bottle delivery opening, a frame, means for successively projecting a plurality of bottles into said opening, a device for rendering the machine inoperable at certain times, an indicator for indicating interruption of the bottle supply, means for operating said bottle-projecting means, including a reciprocating part, and means for operating said operation-obstructing device and said indicator, said last means including a lever having a lost-motion pivotal connection with the frame, a trigger normally engaging one end of said lever to form a fulcrum around which said lever may swing from a first position in which both said operation-obstructing device and said indicator are held in inoperative position to a second position in which said indicator is still inoperative and said device is temporarily operative, said lever being engaged by said reciprocating part when the latter is in its normal position of rest, and thereby held in its first position, and being released so as to assume its second position during each operation of the bottle-projecting means, and means carried by the bottle-projecting means and effective upon an interruption of the bottle supply for causing said trigger to release said lever for pivotal movement around said pivotal connection to a third position in which both said operation-obstructing device and said indicator are rendered operative.

7. In a bottle dispensing machine, a casing having a bottle delivery opening, a bottle conveyor for moving the bottles successively to a position in the vicinity of said opening, means for projecting into said opening a bottle thus positioned, means under the control of the operator for actuating said bottle-projecting means, and means other than said bottle projecting means rendered temporarily effective by said actuating means upon each operation of the machine to prevent a further operation until the cycle of operation is completed.

8. In a bottle dispensing machine, a casing having a bottle delivery opening, a bottle conveyor for moving the bottles successively to a position in the vicinity of said opening, means for projecting into said opening a bottle thus positioned, means under the control of the operator for actuating said bottle-projecting means, means rendered temporarily effective by said last-mentioned means upon each operation of the machine to prevent a further operation until the cycle of operation is completed, and means including a detector controlled by the presence or absence of a bottle at a predetermined point in the line of succession of said bottles for rendering said operation-preventing means permanently effective, until the machine is reset, when there is no bottle present at said point.

9. In a bottle dispensing machine, a casing having a bottle delivery opening, a bottle conveyor for moving the bottles successively to a position in the vicinity of said opening, means for projecting into said opening a bottle thus positioned, means under the control of the operator for actuating said bottle-projecting means, and means including a detector controlled by the presence or absence of a bottle at a predetermined point in the line of succession of said bottles for preventing further operation of the machine until resetting in case there is no bottle present at said point.

10. In a bottle dispensing machine, a casing having a delivery opening, means for feeding bottles successively to an upright position substantially below said opening, and an elevator including a carriage having a laterally projecting finger adapted to extend centrally beneath a bottle disposed in said position, said finger having an upper bottle engaging surface sloping downwardly toward its free end at such an angle that a bottle engaged thereby will slide laterally down said sloping surface, and guide means disposed opposite said elevator for receiving the bottle and guiding it into said opening.

11. In a bottle dispensing machine, a casing having a delivery opening, conveying means for carrying bottles successively to an upright position substantially below said opening, said conveying means including bottle holders suspended from their upper ends so that their lower ends may swing laterally, an elevator including a carriage having a bottle-supporting member and including a vertical portion having a recess disposed above said supporting member and adapted to position a bottle in centered relation to said supporting member, and a guide member carried by said carriage and adapted to engage a bottle approaching said carriage and to swing said bottle laterally to cause the same to clear a side region of said carriage and to enter said recess.

12. In a bottle dispensing machine, a casing having a delivery opening in its top, means for feeding bottles successively to an upright position substantially below said opening, said means comprising an endless conveyor including a plurality of depending bottle holders having lower regions substantially C-shaped in horizontal cross-section and each provided with a bottle-supporting flange projecting inwardly for supporting the bottom of a bottle, and an elevator including a finger adapted to project within the space defined by said C-shaped lower portion, to move upwardly therethrough, and to return downwardly therethrough to its initial position, said finger having the lower side of its outer end inclined downwardly and away from said bottle-supporting flange in the holder so that in the event said flange is contacted by said finger on its downward movement the holder will be moved laterally out of the path of the finger without damage.

13. In a bottle dispensing machine, a casing having a bottle delivery opening in its top, means for conveying bottles successively to a position below and at one side of the axis of said opening, guide means on the other side of said axis, adapted to receive the bottle and guide it into said opening, and elevating mechanism adapted to engage the bottle from below, to first swing the bottle laterally into substantial alignment with said axis, and to then raise the bottle into said opening, said conveying means including a plurality of bottle holders suspended from their upper ends so as to swing laterally under the push of the elevator, each holder including a lower region adapted to contact said guide means when the holder is swung laterally, so as to prevent direct contact between the bottle and said guide means during said lateral swinging movement.

14. In a bottle dispensing machine, a casing having a bottle delivery opening in its top, means for conveying bottles successively to a position below and at one side of the axis of said opening, guide means on the other side of said axis,

adapted to receive the bottle and guide it into said opening, and elevating mechanism adapted to engage the bottle from below, to first swing the bottle laterally into substantial alignment with said axis, and to then raise the bottle into said opening, said conveying means including a plurality of bottle holders suspended from their upper ends so as to swing laterally under the push of the elevator, each holder including a lower region disposed between the bottle and the guide means and adapted to contact the latter during said lateral swinging movement, said lower region having an opening in its bottom and in its side opposite said guide means so as to allow a portion of the elevator to move upwardly therethrough, the upper region of said holder comprising a pair of diametrically opposed arms forming a continuation of said lower region, said arms being spaced apart to provide an opening therebetween forming a continuation of said opening in the lower region, and said holder having on its opposite side another opening above said lower region through which the bottle may be delivered from said holder.

15. In a bottle vending machine, a casing having a bottle delivery opening, an endless carrier for conveying bottles successively to said opening, said carrier comprising a rail, a flanged roller adapted to travel on said rail, a bracket in which said roller is journaled, a chain attached to the upper part of said bracket and positioned above said roller, and a bottle holder attached to and depending from the lower part of said bracket.

16. In a bottle dispensing machine, a casing having a bottle delivery opening, a frame in the upper region of said casing, an endless conveyor suspended below said frame for conveying bottles successively to said opening, said conveyor including a plurality of reaches extending back and forth across the central region of said casing, and a plurality of reaches extending around three sides of the space within said casing and encircling said back-and-forth reaches, said frame having an opening shaped and positioned to give access to one of said encircling reaches and to one or more adjacent return bends of said back-and-forth reaches.

17. In a bottle dispensing machine, a casing having a delivery opening, and an endless conveyor for carrying bottles successively to said opening, said conveyor including a chain, sprockets around which said chain travels, rail sections on which the reaches of said chain between said sprockets are supported, and an adjustment for taking up slack in said chain, including means for adjusting one of said sprockets, a shaft on which said sprocket is rotatably mounted, a bracket carried by said shaft and supporting the ends of two of said rail sections, an adjustable connection between one of said rail sections and said bracket, and an adjustable connection between the other end of the other of said rail sections and said frame.

MAX HERMANN VOIGTRITTER.
